(57) **CLAIM**

The ornamental design for a self-storage carry bag for posters, as shown and described.

DESCRIPTION

FIG. 1 is a front perspective view of the self-storing carry bag for posters showing our new design in its self-stored configuration;

FIG. 2 is a first side elevation view thereof;

FIG. 3 is an opposite side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front perspective view of the self-storing carry bag for posters in an open configuration;

FIG. 9 is a front elevation view thereof;

FIG. 10 is a top plan view of thereof;

FIG. 11 is a side elevation view of thereof;

FIG. 12 is a rear elevation view thereof;

FIG. 13 is an opposite side elevation view of thereof;

FIG. 14 is a bottom plan view thereof;

FIG. 15 is a front perspective view thereof with the upper handles unfastened and spread apart;

FIG. 16 is a front perspective view of the self-storing carry bag for posters in a folded configuration; and,

FIG. 17 is a rear perspective view thereof.
